UNITED STATES PATENT OFFICE.

LAWRENCE I. DENNISON, OF BROOKFIELD, ILLINOIS.

CAN-MAKING MACHINE.

Application filed April 25, 1921. Serial No. 464,116.

To all whom it may concern:

Be it known that I, LAWRENCE I. DENNISON, a citizen of the United States, residing at Brookfield, in the county of Cook and

5 State of Illinois, have invented certain new and useful Improvements in Can-Making Machines, of which the following is a specification.

This invention relates to improvements in 10 can making machinery and more particularly to an attachment for trimming the ends of can bodies or blanks as the same are fed through a so-called lock-seam body-forming machine.

15 In the can making art it is the practice at the present time to cut the can body blanks in a so-called slitting machine, after which said blanks are supplied or fed by suitable mechanism into the so-called lock-seam body-

20 forming machines. In these latter machines these blanks are flanged at their opposite ends and subsequently curved about a horn, or the like, into cylindrical form and in such wise that the flanges interlock, after which a

25 hammer, or the like, presses said flanges firmly together forming the usual lock-seam extending longitudinally of the body. As is well known, slight dimensional variations frequently occur in can body blanks, as the

30 same are cut or formed in the slitting machines, such variations resulting in the production of cans of different sizes and often times the ends of a blank will be cut at a slight angle which prevents the forming of a perfect seam. The can bodies varying in

35 this manner from a given standard must in most cases be scrapped resulting in a total loss.

According to the present invention, it is 40 contemplated to overcome these difficulties and disadvantages by the provision of an attachment primarily adapted for use in conjunction with the so-called lock-seam body-forming machines by means of which 45 attachment each can body blank as the same is fed through the machine is sheared off at its ends, thus avoiding all possibility of dimensional variations in the blanks and the subsequent production of cans of varying sizes, or of cans having poorly formed 50 seams.

Other objects and advantages of the in-

vention will become apparent to those skilled in the art from a reading of the following specification taken in connection with the 55 accompanying drawings wherein one form of the invention is illustrated.

In the drawings: Fig. 1 is a side elevation of a so-called lock-seam body-forming machine shown more or less diagrammatically 60 and many parts being omitted;

Fig. 2 is a top plan view of the machine shown in Fig. 1;

Fig. 3 is a plan view of the attachment which forms the subject matter of the present invention;

Fig. 4 is a sectional view taken on line 4—4 of Fig. 3; and

Fig. 5 is a detail view of one of the cutting blades.

Referring more in detail to the drawings, the lock-seam body-forming machine is shown comprising the usual bed plate 10, and super or supporting structure 11. Extending transversely of the machine near 75 one end thereof is a shaft 12, adapted to be driven from any suitable source through means of the pulley 13, carried at one end thereof. A suitable central longitudinally disposed channel 14 is provided in the top plate of the machine within which channel 80 a plurality of finger bars 15 are reciprocally mounted, each of these bars carrying at intervals throughout its length suitable up-standing dogs or fingers 16. These finger bars 15 are connected by a transverse bar 17, the latter being connected by a suitable link 18 to the upper end of a rocker arm 19. The lower end of this arm 19 is connected 85 by a link 20 to the crank disk 21, carried by shaft 12. Through the mechanism just described the finger bars 15 are reciprocated in unison for the purpose of feeding the can body blanks from a suitable source at the left hand end of the machine—as viewed 90 in Figs. 1—2—through the machine step by step, the fingers or dogs 16 carried by said bars being so arranged that upon movement of the bars in the feeding direction, the upper ends of said fingers extend slightly 95 above the top surfaces of the bars so as to engage the blanks to produce a positive feed or advancement thereof and when moving in 100 a reverse direction drop down below the top

surface of the bars so as not to interfere with or disturb the blanks in their advanced position.

The attachment which forms the subject

- 5 matter of the present invention is designated in its entirety by reference character 22 and is preferably positioned in advance of the other mechanisms which operate upon the blanks so that the said blanks will first be
- 10 cut off square and of proper length. Describing the attachment more in detail, the same comprises supporting plates 23, one mounted on each side of the channel 14. These plates each carry on their inner surface 15 an angle block 24, which may be bolted or otherwise secured to the plates 23. In addition, the blocks 24 may be provided with an outstanding rib designed for engagement within a suitable channel of the blocks 23
- 20 as shown in the drawings. Secured against the exposed face of each of the blocks 24 is a cutting blade 25. These blades, if desired, may be held in position by the same means employed for securing blocks 24 to the plates
- 25 23. Secured to the top plate of the machine and below the cutting blades 25 are bars 26 carrying cutting blocks 27 designed to contact with the cutting blades 25 upon actuation of the attachment. The angle blocks 30 24 are each provided with an overhanging portion 28, apertured as at 29 for receiving stems 30 of suitable presser bars 31, said stems 30 at their upper ends being provided with pins 32 or the like to prevent displacement. The stems 30 are slidably mounted in apertures 29 and coiled springs 33 surround said stems and bear at one end upon the presser bars 31, and at the other end against the overhanging portion 28 of the
- 35 angle blocks 24. The vertical edges of the supporting plates 23 are beveled as at 34 and designed to engage within correspondingly formed grooves in upright guides 35. Each of the supporting plates 23 is reciprocated in a vertical plane by means of a crank disk 36, and connecting rod 37, the crank disks 36 being mounted on a transverse shaft 38, which is driven from the main shaft 12 through the sprocket wheel and chain arrangement shown. The reciprocation of the plates 23 is so timed that the cutting blades 25 will be operated to shear off the ends of each of the blanks as the same are fed through the machine.
- 45 55 In Fig. 4 of the drawings a blank is shown at A beneath the cutting knives and in position to be sheared off at its ends. The function of the presser bars 31 is to clamp or firmly hold blank A against the cutting blocks 27, during the cutting operation so as to prevent displacement thereof and possible improper shearing, the arrangement of said presser bars being such that upon the downward movement of the supporting plates 23 and associated mechanism the said
- 60
- 65

bars are brought into holding engagement with the blank prior to the shearing action of the cutting blades as will be readily appreciated.

After the blank has been trimmed by 70 means of the attachment 22, the same is advanced by the finger bars 15 to the so-called edgers shown diagrammatically in the drawings at 39 where the said blank is flanged at its opposite ends. From this position the 75 blank is again advanced to a position over the horn 40 at which time the cam forming wings 41 are operated to press the blank around the horn in such wise that the flanges formed thereon interlock. The hammer 42 is then thrust upwardly against the interlocked flanges to press the latter firmly together producing the so-called lock-seam. 80

The body forming wings 41 are hinged along their adjacent edges as at 48 and each 85 wing is connected by means of a link 43 to an overhanging rocker arm 44, the latter being connected at its far end to a crank disk 45 by means of the connecting rod 46. The crank disk 45 is carried by a shaft 47 which 90 is also driven from the main shaft 12 by means of the sprocket wheel and chain arrangement shown. It will be understood that all of the mechanisms of the machine are properly timed so as to effect the desired 95 step by step operation upon the blanks as the same are fed through the machine.

Many of the so-called lock-seam body-forming machines as now manufactured are provided with the plates 23, guides 35 and 100 the reciprocating mechanism for said plates previously described, these elements being now employed for the operation of so-called punches designed to notch the can body blanks as the latter are fed through the machine in order to prevent the occurrence of four thicknesses of metal at the ends of the longitudinal body seam when the ends of the can are secured in position. Where these elements do occur in present day machines, 110 the present invention contemplates the association of the trimming or cutting mechanism above described directly with the punching mechanism, so that the blanks will be simultaneously notched and trimmed to 115 size as the same are fed through the machine. In machines where these elements do not occur it will be found a simple matter to install an attachment according to the present invention as well as the operating connections therefor. 120

Attachments constructed in accordance with the present invention are now in use and have proved to eliminate practically all waste of material such as has heretofore 125 been attributable entirely to dimensional variations in the can body blanks due to inaccuracies occurring in the cutting of said blanks in the so-called slitting machines.

As will be readily appreciated by those 130

skilled in the art, the present improvements are susceptible of various changes and modifications and accordingly it is not desired to limit or restrict the same to the particular 5 form or arrangement of parts herein described and illustrated, except where limitations appear in appended claims.

I claim:

1. The combination with a lock-seam 10 body-forming machine, of means associated therewith for squaring the ends of previously cut body blanks as the latter are fed through said machine.

2. The combination with a lock-seam can- 15 forming machine, of an attachment therefor comprising a plurality of guides, supporting plates slidably mounted therein, and

means carried by said plates for squaring the ends of a previously cut blank as the latter is fed through said machine. 20

3. The combination with a lock-seam can- 25 forming machine, of an attachment therefor comprising a plurality of guides, supporting plates slidably mounted therein, means carried by said plates for squaring the ends of a previously cut blank as the latter is fed through said machine, and means associated with said squaring means for holding said blank against displacement during the cutting operation. 30

In testimony whereof, I have subscribed my name.

LAWRENCE I. DENNISON.
